FRACTIONATING AND CONDENSING UNIT

John S. Wallis, New York, N. Y., assignor to Alco Products, Inc., New York, N. Y., a corporation of Delaware

Application October 22, 1932, Serial No. 639,077

8 Claims. (Cl. 196—139)

My invention relates to a fractionating and condensing unit, and more particularly to a combination unit for use with the processing of hydrocarbon oils adapted to combine in a single unit the functions of a fractionating tower and of a condenser.

In the construction known to the art, it is customary to heat a hydrocarbon oil to vaporizing temperature and fractionate it into constituents having different boiling point ranges in a fractionating tower of any suitable design. The uncondensed vapors are withdrawn overhead from the fractionating towers of the prior art and passed to condensers for cooling. It has been developed that fractionation under a vacuum will assist in removing the lighter constituents in a fractionating tower. When fractionation is practiced under a vacuum, the vapors must be condensed under a vacuum. This makes it necessary to keep both the condenser and the fractionating tower under a reduced pressure. While I have mentioned the vacuum fractionation, it is to be understood that my invention hereinafter described is not to be limited to a vacuum operation but may be used in any desired process, the invention being directed chiefly to the construction of my unit.

One of the objects of my invention is to provide a combined fractionating and condensing unit which will perform the work of two individual units as now employed in the art, with a consequent reduction in space and in the cost of construction.

Other objects of my invention will appear from the following description.

In the accompanying drawing which forms a part of the instant specification and which is to be read in conjunction therewith;

Figure 1 shows a sectional view of the unit embodying one method of carrying out my invention.

Figure 2 is a sectional view taken on the line 2—2 of Figure 1.

Figure 3 is a sectional view taken on the line 45 3—3 of Figure 1.

Figure 4 is a sectional view taken on the line 4—4 of Figure 3.

Referring now to the drawing, the tower is formed with a casing 1 of any suitable construction and is provided with a plurality of fractionating decks 2, 3, 4, and 5. It is to be understood that any suitable number of these fractionating decks may be provided. The fractionating decks may be of any suitable construction, the drawing showing a trough construction in which vapors bubble through the liquid which collects in the troughs. The liquid is permitted to overflow and course downwardly through the tower. A stripping section 6 is provided in my tower. While I have shown but one stripping

section, it is to be understood that any number of stripping sections may be employed at suitable places. The stripping section is provided with a perforated steam distributing pipe 7 which is fed through pipe 8. The steam emerging through holes in pipe 7 strips the product passing through the stripping section of its lighter constituents. The stripping section is provided with a pipe 9 through which steam liberated in the stripping section is returned to the point of flash. A pipe 10 is connected to a heater of any suitable design and conducts the oil heated to vaporization temperature to the tower 1, entering through any suitable opening 11. Immediately above the opening 11 are a plurality of baffle plates 12. These baffle plates may be of any suitable construction. In the lower part of the tower, I provide a perforated pipe 13 which is fed by steam through line 14. The function of the pipe 13 is to permit steam to emerge from the perforations thereof to strip the residue collecting in the lower part of the tower 15 of its lighter constituents. The part of the tower which is described constitutes the fractionating part of my unit. The vapors which will be composed of hydrocarbon fractions having lower boiling point ranges will pass the uppermost deck 2 in the form of vapors through passages 20 and 21 formed by a housing 17 with the casing 1 as shown by the arrows in Figure 1. The vapors rising through passages 20 and 21 will reach the partition 22 and be deflected downwardly in contact with the cooling bank 23 of the condenser 24. This condenser may be of any suitable construction. It is provided with pipes 25 and 26 through which cooling water is fed through the tube bank 23. The light hydrocarbon vapors coursing downwardly in contact with the cool tubes will have a part of the constituents thereof condensed. The condensate will collect in receiver 30. Receiver 30 is provided with a withdrawal pipe 31 through which the condensate is withdrawn. Likewise, an overflow pipe 32 is provided for refluxing a portion of the condensate to the uppermost fractionating deck 2. It is to be understood that the fractionating decks 2, 3, 4, etc. may be provided with drawoffs for withdrawing the fractions which collect thereon, as for example, the pipe 28 which is fitted in the stripping section 6 for withdrawing the stripped product therefrom. The uncondensed vapors and incondensable gases will pass upwardly through conduits 40, 41, 42, and 43 as can be seen by reference to Figures 3 and 4. These gases and vapors must pass in contact with additional condensing means provided at the uppermost part of the tower. A plurality of decks 50, 51, 52, and 53 are provided. These decks have suitable perforations such as 54, 55, and 56 permitting liquid on one of the 60

decks to pass to the deck below. The lower decks are provided with apertures having flanges therearound to govern depth of the liquid on the decks 50, 51, and 52. Water through pipe 57 is discharged on the upper deck 53 and courses downwardly, collecting on the lower decks, and overflowing as can be readily seen by reference to Figure 1.

Uncondensed vapors and incondensable gases 10 pass upwardly through the spray or rain of water and are thus cooled. The water collects in a receptacle or basin of any suitable design 60 and is withdrawn through line 61 which passes to the hot well 62. The upper portion of the 15 tower terminates in a suitable connecting means to which is connected a barometric condenser 72 through a line 71. High pressure steam through line 73 passes to the jets of the barometric condenser 72. Steam from steam jets 74 and 72 20 passes downwardly through lines 75 and 76 to the hot well 62. The barometric condenser using steam jets is well known in the art and any suitable type may be used. It is to be understood that, while I have shown the steam jets 25 as a means of keeping my unit under reduced pressure, that I may eliminate the vacuum maintaining means if an atmospheric distillation operation is desired.

In operation, the oil vapors heated to vaporizing temperature in a still or any suitable apparatus, enter my unit through line 10. The heated oil flashes into vapors after leaving inlet 11. The vapors course upwardly through my unit 30 and condense on the various decks of the fractionating portion of the tower, according to the boiling point ranges thereof. The fractions which collect on the decks will overflow and course downwardly through the tower. A portion of this downwardly coursing condensate 35 may be stripped in suitable stripping sections. The lighter vapors pass upwardly and are condensed in my condensing section. The uncondensed vapors are cooled by contact with a cooling medium and are withdrawn by means of 40 barometric condensers or any suitable vacuum means. It is believed that the operation will be clear from the foregoing description.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I 60 claim is:

1. A fractionating and condensing unit comprising in combination a casing, a plurality of fractionating decks extending across said casing, a housing mounted within said casing above the uppermost of said decks, a partition extending across said casing above and spaced from said housing, condensing means mounted within said housing, a condensate receiving means mounted below said condensing means, a duct 65 leading from said housing through said partition for leading the uncondensed vapors above said partition, a connection for introducing heated vapors into the casing and a connection for withdrawing the condensate.

2. A fractionating and condensing unit comprising in combination a casing, a plurality of fractionating decks extending across said casing in spaced relation to each other, said decks being provided with openings for the passage of vapors therethrough, a housing mounted within said casing above said decks, the upper portion of said housing being provided with an opening for the passage of vapors thereinto, condenser tubes positioned in the upper portion of said housing adapted to condense a portion of the vapors, the lower portion of said housing being free of tubes and adapted to collect the condensate, means for withdrawing the uncondensed vapors and incondensable gases from said housing and means for withdrawing the condensate.

3. A unit as in claim 2 including means mounted within said casing for directly contacting the uncondensed vapors withdrawn from said housing with a cooling medium.

4. A fractionating and condensing unit comprising in combination a casing, a plurality of fractionating decks extending across said casing in spaced relation to each other, said decks being provided with openings for the passage of vapors therethrough, a housing mounted within said casing above the uppermost of said fractionating decks, the upper portion of said housing being provided with an opening for the passage of vapors thereinto, condenser tubes positioned in the upper portion of said housing adapted to condense a portion of the vapors, the lower portion of said housing being free of tubes and adapted to collect the condensate, means for withdrawing the uncondensed vapors and incondensable gases from said housing and means for withdrawing the condensate, and an overflow means communicating with said housing for permitting a portion of the condensate to flow to the highest fractionating deck after a predetermined level of condensate has been reached within said housing.

5. A unit as in claim 2 including means for maintaining said casing under sub-atmospheric pressure.

6. A unit as in claim 4 including means for maintaining said casing under sub-atmospheric pressure.

7. A fractionating tower including in combination a shell, a plurality of fractionating decks within said shell, a housing mounted within said shell above said decks and spaced from the interior surfaces thereof to form a vapor passage, said housing being provided with an opening communicating with said passage and in the upper portion of said housing, a condenser positioned in the upper portion of said housing, the lower portion of said housing being free of tubes and forming a condensate receiver, a condensate drawoff line from said receiver and a duct communicating with said housing for withdrawing uncondensed vapors therefrom.

8. In a fractionating tower a partition extending across the interior thereof, a housing suspended from said partition and mounted in spaced relation with the interior walls of the fractionating tower to form a vapor passage, a vapor inlet from said passage into the upper portion of said housing, a condenser mounted in said housing, and means forming a duct extending from said housing below said condenser through said partition for conducting uncondensed vapors thereabove.
